Patented Dec. 30, 1924.

1,520,835

UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

METHOD OF RECEIVING ELECTRICAL OSCILLATIONS.

No Drawing.

Application filed September 3, 1921. Serial No. 498,414.

(GRANTED UNDER THE PROVISIONS OF THE ACT OF MARCH 3, 1921, 41 STAT. L., 1313.)

To all whom it may concern:

Be it known that I, ALEXANDER MEISSNER, citizen of the German Republic, residing at Berlin, Germany, have invented certain new and useful Improvements in Methods of Receiving Electrical Oscillations, for which I have filed applications as follows: 5 Germany, Patent No. 285,279, filed Oct. 14, 1913; Argentina, Patent No. 11,269, filed Feb. 27, 1914; Australia, Patent No. 34,487, filed Feb. 17, 1914; Belgium, Patent No. 263,703, filed Jan. 12, 1914; Brazil, Patent No. 8,241, filed Apr. 15, 1914; Chile, Patent No. 3,094; Denmark, Patent No. 21,068, filed 10 Dec. 4, 1914; England, Patent No. 252/14, filed Jan. 5, 1914; France, Patent No. 467,747, filed Jan. 27, 1914; Holland, Patent No. 3,267, filed Jan. 22, 1914; Italy, Patent No. 422/242, filed Jan. 12, 1914; Mexico, 15 Patent No. 15,059, filed Apr. 14, 1914; New Zealand, application No. 34,487, filed Feb. 28, 1914; Austria, Patent No. 79,829, filed Jan. 7, 1914; Peru, filed March 19, 1914; Rumania, Patent No. 3,761, filed March 18, 20 25 30

1914; Sweden, Patent No. 40,257, filed Feb. 4, 1914; Spain, Patent No. 57,310; Turkey, Patent No. 2,298, filed Feb. 26, 1914; Hungary, application No. T. 2,383, filed Jan. 29, 1914; Tschechien, Patent No. 4,097, filed Jan. 2, 1920, of which the following is a specification.

As is well known, there are wireless telegraph receiving arrangements operable in a manner such that through the mutual effect of the oscillations received and auxiliary oscillations produced at the receiving station and having a frequency differing slightly from the received frequency, vibrations will be generated which will produce 35 musical sounds.

The present invention relates to a method of receiving radio energy in accordance with which the frequency of the auxiliary oscillations does not lie near to the fundamental frequency of the received oscillations, but, on the contrary, is differentiated from a multiple or aliquot part of the fundamental frequency of the energy to be received. It has been found that musical sounds will be 45 produced whenever the frequency of the auxiliary oscillations differs by an audio 50

frequency from a multiple or aliquot part of the oscillation to be received.

Under certain conditions, the use of auxiliary oscillations having a frequency approaching a multiple or aliquot part of the fundamental frequency of the received oscillations, as the case may be, has several technical advantages over the use of nearly equal auxiliary and received frequencies. 55 Of such advantages, the following may be mentioned:

When arc lamp generators are used for producing auxiliary oscillations at the receiving station for heterodyning the oscillations being received, it is preferable to give the auxiliary oscillations a frequency which is materially smaller than the frequency of the received energy, because the greater the wave length, the less the effect of irregularities in the oscillations generated by the arc lamp. Accordingly, the lower the frequency of the arc lamp generator, the clearer are the sounds obtained.

If it is desired to receive damped oscillations produced by a spark sender, the frequency of the oscillations produced at the receiving station being lower than or approximately equal to the fundamental frequency of the oscillations being received, under no circumstances will a clear tone be produced if the damping of the received oscillations is not exceptionally weak, because it is very unlikely that during a series of undulations of the received energy a sufficient interference effect will be produced to effect an impulse on the telephone diaphragm. Therefore, in this case it is of particular advantage to give the oscillations produced at the receiver a frequency that is 75 80 85 90

higher by almost a multiple than the oscillations received, because then the possibility will be greater that one or a plurality of complete vibrations will be produced during the dying out of the series of undulations of the damped sender. In this manner, the telephone diaphragm will be actuated to give a clear sound, whereas in the other case only irregular noises are perceptible.

Having described my invention what I 100 claim is:

1. A method of receiving electrical oscilla-

tions which includes heterodyning the received energy by current, the frequency of which differs by an audio frequency from a multiple of the fundamental frequency or 5 the received energy.

2. A method of receiving electrical oscillations which includes heterodyning the received energy by current, the frequency of 10 which differs by an audio frequency from a frequency which bears with the fundamental frequency of the received energy an integral ratio in which either the fundamental frequency or the last-named frequency may be represented by unity.
- 15 3. A method of receiving electrical oscillations which includes heterodyning the received energy by current, the frequency of

which approaches more nearly to a multiple of the fundamental frequency of the received energy than to the fundamental frequency. 20

4. A method of receiving electrical oscillations which consists in generating an electric current at the receiver, producing by combination of the received energy and said locally generated current a current, the 25 frequency of which is equal to the difference between the frequency of the locally generated current and a multiple of the fundamental frequency of the received energy, and utilizing said second-mentioned current to 30 actuate an indicator.

In testimony whereof I affix the signature.

ALEXANDER MEISSNER
